UNITED STATES PATENT OFFICE.

HENRY C. PERDUE, OF VALPARAISO, INDIANA, ASSIGNOR TO MORGAN CONSTRUCTION COMPANY, OF WORCESTER, MASSACHUSETTS, A CORPORATION OF MASSACHUSETTS.

GAS-PRODUCER.

1,284,138.

Specification of Letters Patent.

Patented Nov. 5, 1918.

Application filed June 1, 1914. Serial No. 842,053.

To all whom it may concern:

Be it known that I, HENRY C. PERDUE, a citizen of the United States, residing at Valparaiso, in the county of Porter and the 5 State of Indiana, have invented a new and useful Improvement in Gas-Producers, of which the following, taken in connection with the accompanying drawings, is a specification.

10 The present invention relates to gas producers, and in particular to mechanism adapted for evening or smoothing the surface of the bed of fuel in a gas producer, whereby to insure a fuel bed which is homogeneous in character and of uniform thickness. To this end it is proposed to suspend a member within the combustion chamber of the producer in contact with the surface of the bed of fuel therein, and to cause relative movement between said member and the fuel, in order to obtain an evening of the surface of the fuel. One object of the present invention is to secure a suitable means of support for such a member in order to provide for its vertical adjustment to correspond to changes in the level of the fuel bed. Another object is to provide for an adjustment of said evener member in the plane of the surface of the fuel in order to obtain variations in the action of said member in crowding the surface fuel toward or from the center of the producer. Other and further objects will appear from the following description and claims, taken in connection with the accompanying drawings, in which—

Figure 1 is a top plan view of a gas producer equipped with my invention, a portion of the latter being shown in section, on line 1—1, Fig. 2.

Fig. 2 is a vertical section on the line 2—2, Fig. 1.

Fig. 3 is a horizontal section on the line 3—3, Fig. 2.

Like reference characters are used to designate like parts in the different figures.

The numeral 1 indicates the fuel supporting section of a gas producer, which is adapted to be rotated, when the producer is 50 in operation, by any suitable mechanism such as a rack 2 and intermeshing pinion 3. Suitably supported above the fuel section 1 of the producer, and stationary with respect thereto, is an upper section 4, having 55 a depending annular apron 5 extending into

an annular water chamber 6 of the section 1 to provide a water seal against the escape of gases from the interior of the producer. The top of stationary section 4 is closed by a cover plate 7, which is preferably formed 60 with an upstanding rim 8 to provide a water chamber, in order to avoid overheating of said plate. At one side of its center said plate is formed with an elongated opening 9, extending substantially radially thereof 65 and defined by upstanding lateral walls 10, 10 which diverge slightly from the longitudinal center of said opening, as seen in Fig. 3, and curved segmental end walls 11, 11 of equal height. Rising from the cover 70 plate 7 beyond each wall 10 are the even more divergently directed walls 12, 12 which are joined by similar curved segmental end walls 13; the said walls 12 and 13 and 10 and 11 forming a water chamber, preferably 75 of greater depth than the cover plate water chamber, entirely surrounding the opening 9.

The cover plate 7 supports a pair of vertical posts 14, one on each side of the longitudinal center of the opening 9. Said posts are joined at their upper ends by a cross beam 15, which is enlarged at its central portion and provided with an opening for the passage of a cylindrical shaft 16, guide 80 wheels 17, 17 being provided adjacent said opening in contact with opposite sides of said shaft to insure its free movement within said opening. The shaft 16 has its lower end extending into and rigidly secured to 85 a trough-like member 18 which constitutes the evener member of this invention, said member 18 being rectangular in cross section and of substantially less cross sectional area than the opening 9 through which it 90 projects on either side. The closed lower end of said member 18, which is adapted to contact with the surface of the fuel, is preferably formed of a separate casting 19, having 95 its lower surface inclined upwardly, as shown in Fig. 2, toward the side from which the fuel advances. The open upper end of said member 18 is flanged outwardly and is provided with a depending apron 20 of the same general shape as the walls 12 and 13 100 but of substantially less width, to permit limited angular movement of said apron within the water chamber inclosed by said walls, with which said apron coacts to form 105 a water seal around said opening.

The upper end of shaft 16 has mounted thereon a collar 21, which is restrained from longitudinal movement upon said shaft, but is free to rotate with respect thereto. Said 5 collar has oppositely extending trunnions 22 thereon, adapted to engage within elongated slots 23 formed in the two forks of a lever 24, pivoted at 25 upon an extension of one of the posts 14. On the other side 10 of its fulcrum a pivotally attached link 26 extends downwardly from said lever, the said link being attached by means of a turnbuckle 27 to the upper end of a fixed member 28. It is obvious that the vertical position 15 of the evener within the producer may be changed by a simple adjustment of the turnbuckle 27, and for the purpose of rendering this adjustment easy, a weight 29, carried on the free end of lever 24, is employed to substantially counterbalance the weight of the evener.

The shaft 16 has extending from opposite sides thereof a pair of lateral arms 30, which have enlargements 31 on their outer ends 25 provided with elongated segmental slots 32 through which the posts 14 pass. At each end, each of said slots has a screw threaded hole receiving a screw 33 bearing at its inner end against a shoe 34, said shoes being suitably guided for sliding movement longitudinally of the respective slots. Each screw 33 holds its shoe against the side of the corresponding post 14, in order to hold the evener member 18 and the shaft 16 from rotation. By proper adjustment of the screws 33 it will be apparent that the angular position of the evener member 18, with respect to a radius of the producer, can be varied within the limits defined by the width of 40 the opening 9.

The construction of the evener member 18 renders it peculiarly adaptable to water cooling; the interior of said trough is at all 45 times accessible from the top of the producer to permit of its being cleaned of deposits of mud and scale while the producer is in operation. Furthermore, the means by which the evener member is supported are readily detachable to permit the removal of said 50 member for replacement or repairs.

In the operation of the evener, the turnbuckle 27 is adjusted to bring the bottom surface of the evener into proper operating position, as determined by the mean level of 55 the fuel in the rotating section 1. The rotation of the bed of fuel brings all portions of its surface into contact with said evener, with the result that all inequalities in the surface of the fuel are eliminated. Fresh 60 fuel, fed through a suitable hopper or feeding device 35 is almost immediately carried into contact with the member 18, and is thereby spread evenly over the surface of the fuel bed. It will be obvious that instead of rotating the fuel section 1 to carry 65

the surface of the fuel into contact with the evener, the section 1 may be held stationary and the section 4 or the cover plate 7 rotated to carry the member 18 into contact with all portions of the surface of the fuel.

When the member 18 occupies a radial position with respect to the producer, the fuel with which it is brought into contact has a tendency to work gradually toward the outer wall of the fuel section 1. By adjusting 75 the screws 33, the evener may be made to assume a position at an angle to said radial position, with its outer end moved slightly toward the advancing fuel, as shown in Figs. 1 and 3. Such an adjustment has a tendency to neutralize the crowding of the fuel against the outer wall of the producer, and if desired, the member 18 may be so positioned as to cause the fuel to be crowded toward the center of the producer. This 80 horizontal adjustment of the evener is a highly desirable feature of my invention, and is readily effected when the producer is in operation.

I claim:—

1. In a gas producer, a rotatable fuel section, a stationary member disposed therein, in scraping contact with the surface of the fuel, and means for varying the position of said member in the plane of the surface of the fuel, whereby the action of said member in crowding the fuel toward or from the center of the fuel section is varied.

2. A gas producer, a fuel section, a member disposed therein to make contact with the surface of the fuel bed during the continuous operation of the producer, means for causing a relative traversing movement between said member and the surface of the fuel, and means for adjusting the position of said member about an axis offset from the axis of said section.

3. In a gas producer, a fuel section, a member disposed therein to make contact with the surface of the fuel bed continuously during the operation of the producer, means for causing a relative traversing movement between said member and the surface of the fuel, and means for adjusting the position of said member about an axis parallel to the axis of said section.

4. In a gas producer, a fuel section, a fuel evener adapted to lie in contact with the surface of the fuel in said section during the continuous operation of the producer, means for causing a relative traversing movement between said fuel evener and the surface of said fuel, means for adjusting said fuel evener to correspond to changes in the level of the fuel in said fuel section, and means for adjusting said fuel evener in the plane of the surface of said fuel.

5. In a gas producer, a rotating fuel section, a stationary fuel evener within said fuel

section, and means for adjusting the position of said fuel evener with respect to the axis of said fuel section.

6. In a gas producer, a fuel section, a fuel evener within said fuel section continuously in contact with the bed of fuel during the operation of the producer, means for causing relative movement between said fuel evener and the surface of said fuel, and means for adjusting the angular position of said fuel evener in the plane of the surface of said fuel.

7. In a gas producer, a rotating fuel section, a stationary fuel evener within said fuel section, means for vertically adjusting said fuel evener, and means for horizontally adjusting said fuel evener.

8. In a gas producer, a rotating fuel section, a stationary cover section having an opening therethrough, a fuel evener carried by said cover section and projecting through said opening, means for adjusting said fuel evener, and means for sealing said opening against the escape of gas in all positions of adjustment of said fuel evener.

9. In a gas producer, a section having an opening therethrough, a water chamber sur-

rounding said opening, an elongated fuel evener within said opening, having an apron extending into said water chamber and means for changing the position of said member within said opening, without destroying the water seal provided by said apron and said water chamber.

10. In a gas producer, a fuel evener comprising a hollow member adapted to contain a body of water, said member being open at the top and projecting beyond the wall of the gas chamber of said producer, a water chamber, and a flange depending from said member into said water chamber.

11. A fuel evener for a gas producer, comprising a hollow member, open at its top, a vertically adjustable member connected to said hollow member, said vertically adjustable member having arms extending therefrom, and means co-operating with said arms to control the position of said hollow member with respect to the axis of the producer.

Dated this 26th day of May, 1914.

HENRY C. PERDUE.

In the presence of:—

WILLIAM E. EVANS,
CLARENCE T. WILSON.
